UNITED STATES PATENT OFFICE.

CHARLES CHESTER STEWART, OF DODGE CITY, KANSAS.

ROTARY ROAD-GRADER.

1,334,001.

Specification of Letters Patent. Patented Mar. 16, 1920.

Application filed May 2, 1919. Serial No. 294,327.

To all whom it may concern:

Be it known that I, CHARLES C. STEWART, a citizen of the United States, residing at Dodge City, in the county of Ford and State of Kansas, have invented certain new and useful Improvements in Rotary Road-Graders, of which the following is a specification.

My invention consists of a rotary road grader of a type carrying a grading tool adapted for rotation and operation in substantially horizontal planes.

Rotary road graders or excavators generally operate upon a vertical plane and are limited in the width of excavation made. In cases where the purpose sought is the grading of a roadway of substantial width scrapers operating upon a narrow width must be driven a number of times over substantially the same length of road. Where such graders of wide area are used, provision must be made for considerable power to haul the machine, due to the large increase in resistance offered by the wide sweep in the material.

By utilizing a rotary cutting tool operating in the horizontal plane, I have found it possible to grade a substantial width of path at one operation with the added saving in time and energy required to draw the grader over the ground.

A further object of my invention consists in the operation of a rotary cutting tool utilizing a portion of its edge as a fulcrum relatively stationary in the ground and serves to multiply the cutting force created by the forward movement of the machine.

A further object of my invention is in improvement in the means for adjustment as will be shown hereinafter and described.

In the drawings:—

Figure 1 shows a side elevation of a vehicle embodying my improvements;

Fig. 2 shows an end view and indicates in what manner adjustment may be made of the plane of cutting;

Fig. 3 is a plan view of the device; and

Fig. 4 is a horizontal section of certain adjustment features, said section being taken on the line 4—4 of Fig. 1.

Fig. 5 is a section on line 5—5 of Fig. 3.

The vehicle 5 forms the structure for carrying the grader. The vehicle is pivotally mounted at its forward end on the pair of wheels 6, while the wheels 7 mounted on axle 8 serve to support the rear of the ve-

hicle. The axle 8 is made laterally slideable in the frame of the vehicle and on its rear portion carries a toothed rack 9. Vertically journaled in the frame of the vehicle adjacent the axle 8 will be found the shaft 10 carrying a toothed pinion in engagement with the rack 9. By means of the hand wheels 11 mounted on the shaft 10, the axle 8 and the wheels carried thereby may be adjusted laterally for the purpose of determining the position of the grading movement of the cutter, hereinafter mentioned.

Centrally mounted on the vehicle is the frame 12, rigidly reinforced by means of the horizontal struts 14 and the inclined struts 13.

The cutting tool, designated generally as 15, consists of a cylindrical member 16, the lower flange of which 17 performs the cutting function. The member 15 is mounted on the rim 18 of the large wheel 19. The spokes 20 of this wheel radiate from a hub 21. Keyed to the hub 21 is the solid shaft 22. The spokes 20 constitute reinforcing members in a vertical direction as indicated in Fig. 1.

The shaft 22 is journaled at 23 and 24 in the hollow tube 25. This tube 25 is supported pivotally in the block 26 by means of the antifriction rollers 27. Vertical adjustment of the tube 25 is permitted by means of a cable 28 extending from the top to the bottom of said tube on the outside, and its middle portion wrapped around and fastened to a transverse shaft 29 journaled in the frame in the bearings 30. One end of the shaft 29 carries the gear 31 in mesh with the worm gear 32. The worm gear 32 is journaled in the bearings 33 and terminates at one end in the universal joint 34. To this universal joint is attached a shaft 35 carrying a hand wheel 36.

The structure 12 is longitudinally recessed to carry the block 26 movably adjustable in a longitudinal direction. Means for this adjustment is provided by the shaft 37 engaged in a thrust bearing 38 of the block 26 and screw threaded as at 39 in the structure 12. A universal joint 40 connects the shaft 36 to a shaft 41. Upon the shaft 41 is mounted a hand wheel 42.

The chain 43 extending from the forward part of the frame connects with a ring 44 at the base of the tube 25. This chain permits the tube to be pivoted in a longitudinal plane backward of the vertical position

shown in Fig. 1 and provides for an adjustment in the depth of cutting. The ring 44 carries on opposite sides eyelets to which are attached the lateral adjusting chains 45. The upper ends of these chains are fastened to shafts 47. The shaft 47 is carried vertically in bearings on the frame and carries keyed to its upper end a gear wheel 48. This gear wheel is in mesh with 10 the spiral threaded shaft 50 which is carried horizontally in bearings 49 on the frame. A universal joint 51 transmits motion to this shaft from the operating shaft 52. By means of the hand wheels 53 mounted on 15 shafts 52 it is possible to tilt the cutting member and thus adjust the inclination of the surface cut. It will be obvious that where one of the chains 45 is shortened, the opposite one will be lengthened. The two, 20 after adjustment, will form a rigid reinforcement for the tube 25.

From the above description it will be evident that this machine provides means to control the adjustment of the cut which it 25 is desired to make in the ground traversed by the device.

The requisite inclination is given to the tube in a lateral direction providing that one side edge 17 will penetrate the ground. 30 This side edge now becomes the fulcrum and the forward movement of the vehicle will cause the cutting disk 15 to rotate around the relatively stationary side edge, causing the advance of the rear edge 17 and its corresponding result of scraping such material 35 as is found above its edge and carrying it to the opposite or elevated side of the cutter 15. This material having been conveyed and elevated above the natural surface of 40 the earth will be delivered from within the cutter wheel 16. By adjusting the laterally extending chains 45 the inclination of the finished roadway can be determined and varied. It will also be possible, when using 45 this machine for throwing up a ditch or dike, to give sufficient inclination so that the material delivered from the upper side of the cutting member is raised with the least possible expenditure of power and to 50 the highest possible point. The use of one side of the cutter as a fulcrum about which the cutter will turn provides for a minimum of energy to be expended in the grading operation and a corresponding minimum 55 of friction loss between the cutter and the ground. In this case the cutter moves with the material that is to be carried and delivered to the side and there is, relatively speaking, no frictional loss caused by the 60 sliding of the material along the surface of the cutter blade.

The particles of material excavated by the depending inner surface of the rotating flange at its lowest point, as shown in Fig. 65 2, are compelled to travel laterally of the

machine. As indicated in Fig. 3, this portion of the flange travels laterally with the material until it reaches a point directly in rear of the lower point of the tube. At the same time the flange is rising due to the 70 tube's inclination and at this point the material is discharged beneath the edge of the flange.

This portion of the flange then continues its free rotation, successively rising and falling until it penetrates a new portion of the road or other material to be excavated at the lower limit of the flange's travel. The initial engagement with the earth is substantially without lateral movement. It follows that the forward movement of the vehicle advances the shaft beyond this point as a fulcrum and promotes the effectiveness of that portion of the flange which is at this moment excavating and conveying the material. 80

The path of the operating portion of the flange, which is taken as an example of the operation of all parts of the flange, is that generally termed cycloidal. 90

The cable 28 is sufficiently loose so that no strain will be imposed upon the tube 28 during the operation of tilting the latter in a rearward direction.

What I claim is:

1. In a grading machine, a shaft journaled for rotation therein, a circular cutting blade mounted on the lower end of said shaft, and means for depressing the rear portion of said cutting device. 95
2. In a grading machine, a shaft journaled for rotation therein, a circular member mounted on the lower end of said shaft at right angles thereto, a cutting flange carried by said member and means for depressing the rear portion of said member. 100
3. In a grading machine, a shaft journaled for rotation therein, a circular member mounted on the lower end of said shaft at right angles thereto, a cutting flange depending from said member and means to incline the axis of the shaft laterally of the machine. 110
4. In a grading machine, a shaft journaled for rotation therein, a circular member mounted on the lower end of said shaft at right angles thereto, a cutting flange depending from said member and means to adjust the shaft vertically. 115
5. In a grading machine, a shaft journaled for rotation therein, a circular cutting blade mounted on the lower end of said shaft, means to adjust said shaft vertically, and means to incline said shaft longitudinally of the machine. 120
6. In a grading machine, a shaft journaled for rotation therein, a circular cutting device mounted on the lower end of said shaft, means to adjust said shaft vertically, means to incline said shaft longitudinally 125
7. In a grading machine, a shaft journaled for rotation therein, a circular cutting device mounted on the lower end of said shaft, means to adjust said shaft vertically, means to incline said shaft longitudinally 130

of the machine and means to incline said shaft laterally of the machine.

7. In a grading machine, a shaft journaled for rotation therein, a circular member mounted on the lower end of said shaft at right angles thereto, a cutting flange carried by said member adapted to excavate material at one side of the machine.

8. In a grading machine, a shaft journaled for rotation therein and inclined from the vertical, a circular member mounted on the lower end of said shaft at right angles thereto, a cutting flange carried by said member adapted to excavate material at one side of the machine and to convey the excavated material to the opposite side.

9. In a grading machine, a shaft journaled for rotation therein, and inclined from the vertical, a circular member mounted on the lower end of said shaft at right angles thereto, a cutting flange carried by said member adapted to excavate and convey material, said member being rotatable by the travel of the machine.

25 10. In a grading machine, a tube, means to adjust said tube vertically, means mounted

on opposite sides of the machine to adjust the tube laterally, means to position the tube longitudinally of the machine and a circular cutting member journaled in the lower end of the tube.

11. In a grading machine, a tube mounted therein, a shaft carried by said tube and adapted for free rotation therein, means mounted on opposite sides of the tube to adjust said tube laterally, means to position the tube longitudinally of the machine, and means to adjust the tube vertically, the said several adjusting means operable from a remote portion of the machine.

12. In a grading machine, a shaft journaled for rotation therein, a circular member mounted on the lower end of said shaft at right angles thereto, a cutting flange carried by said member adapted to excavate and convey material to one side of the machine, means to incline said shaft laterally, a traction member in rear of said circular member, and means to shift said traction member with respect to said circular member.

In testimony whereof I affix my signature.
CHARLES CHESTER STEWART.
